UNITED STATES PATENT OFFICE.

JOHN S. ALGEO, OF WHEELING, WEST VIRGINIA, ASSIGNOR TO HAZEL-ATLAS GLASS COMPANY, OF WHEELING, WEST VIRGINIA, A CORPORATION OF WEST VIRGINIA.

DESIGN FOR A GLASS DECANTER.

Application filed March 12, 1924. Serial No. 8,907. Term of patent 14 years.

To all whom it may concern:

Be it known that I, JOHN S. ALGEO, a citizen of the United States, residing at Wheeling, in the county of Ohio and State of West Virginia, have invented a new, original, and ornamental Design for Glass Decanters, of which the following is a specification, reference being had to the accompanying drawing, forming part thereof.

Figure 1 is a view of the glass decanter in elevation; and

Figure 2 is a bottom plan view of the decanter.

I claim:

The ornamental design for a glass decanter, as shown.

JOHN S. ALGEO.
